WILLIAM R. KNIGHT, OF BELLEVILLE, NEW JERSEY, ASSIGNOR TO ST. MUNGO MANUFACTURING COMPANY OF AMERICA, OF NEWARK, NEW JERSEY, A CORPORATION OF NEW JERSEY.

PLAYING-BALL.

1,194,751.

Specification of Letters Patent. Patented Aug. 15, 1916.

Application filed January 31, 1916. Serial No. 75,264.

To all whom it may concern:

Be it known that I, WILLIAM R. KNIGHT, a subject of the King of Great Britain, and a resident of Belleville, county of Essex, 5 and State of New Jersey, have invented new and useful Improvements in Playing-Balls, of which the following is a specification.

The object of the invention is to construct a playing ball with means which will place 10 the ball under control in all departments of the game in which it is employed.

According to my invention the ball may be provided with a center having a heavy liquid that will aid its flight.

15 The invention preferably relates to that class of playing-balls that are especially adapted for the purpose of golfing and which have a liquid center. In performing my invention a playing-ball is constructed 20 with a bag or container within which there are liquids of different specific gravities. The weight of the ball is dependent to a certain extent upon the particular combination of liquids chosen and the amount of each 25 liquid employed. With the proper selection of liquids a ball may be made comparatively heavy; that is the ball may be what is known as a non-floating ball or the ball may be made comparatively light, that is the ball 30 may be what is known as the floating type of ball.

As illustrating the manner in which the invention may be realized reference is made to the accompanying drawing which forms 35 a part of this specification and in which drawing—

Figure 1 illustrates a playing-ball partially broken away so as to show its interior construction. Fig. 2 shows a core partially 40 broken away which is utilized in the ball shown in Fig. 1.

The playing-ball comprises a bag or container A that is filled with incompressible liquids of different specific gravities as B and F, B being the lighter liquid and F the heavier liquid. The bag or container A and the liquid thus constitute the nucleus or core of the ball. Around this core there is preferably wound under a high degree of tension 45 a rubber tape that may be for example approximately one inch in width. This rubber tape is comparatively thin and when wound under a high degree of tension imparts great pressure upon the liquid in the bag or con-

tainer A. The windings of tape are indicated by the reference character C and around these windings of tape there is wound under a high degree of tension what may be considered a thread of rubber which thread before winding may be approximately three 60 thirty-seconds of an inch in width. These windings of rubber thread are indicated by the reference character D. Finally there is placed upon and around these windings any suitable wear-resisting casing E, for example of gutta percha, which constitutes the exterior portion of the ball. The bag or container A is made so as to comprise the rubber portion a^1 and a fabric portion a^2 that constitutes a reinforcing member or protecting 65 member for the rubber in the casing.

It has been previously indicated that any one of several combinations of liquids may be employed within the bag or container A, dependent upon the kind of ball ultimately 75 desired. For example, if a heavy ball is desired the liquid within the bag or container A may comprise water for the lighter liquid B and mercury for the heavier liquid F. If a ball of a different weight is desired acetylene tetrabromid may be employed for the heavier liquid and amyl formate for the lighter liquid. The former of these has a specific gravity of approximately 3. and the latter a specific gravity of approximately 85 .686. If a floating ball is desired heptane may be employed for the lighter liquid and amyl formate for the heavier liquid. The specific gravity of heptane is approximately .689 while that of amyl formate as above indicated is approximately .868. Other combinations which might be used are as follows, but it will be understood that a large number of combinations could be employed other than those indicated in this specification. 90 Methyl salicylate and amyl formate the relative specific gravities of which are respectively 1.185 and .868. Heptane and water the relative specific gravities of which are approximately .689 and 1.00.

The liquids in the different sets of combinations above referred to are not soluble in each other; in other words they are of such a character that they do not tend to mix but on the other hand tend to separate and remain separated with the lighter liquid floating on the heavier liquid, and the expression in the several claims to the effect that liquids

do not mix with each other is intended to convey the meaning that these liquids will tend to separate and tend to remain separated if allowed to do so.

5. It will be manifest that the invention may be embodied in various forms and modifications without departing from the spirit and scope thereof.

What I claim is:

10. 1. A playing-ball comprising in combination a bag or container filled with a plurality of liquids of different specific gravities, windings of rubber surrounding said bag, and a wear-resisting casing on the exterior 15 of said windings.

20. 2. A playing-ball comprising in combination a bag or container filled with liquids of different specific gravities which liquids are of such a character that they tend to separate from each other, rubber windings surrounding said bag or container, and a wear-resisting casing on the exterior of said windings.

25. 3. A playing-ball comprising in combination a bag or container having therein a plurality of liquids of different specific gravities and which liquids are of such character that they do not mix with each other, windings surrounding said container, 30 and a wear-resisting casing surrounding said windings.

35. 4. A playing-ball comprising in combination a bag or container having therein incompressible liquids of different specific gravities, windings surrounding said container, and a wear-resisting casing surrounding said windings.

40. 5. A playing-ball having in combination a bag or container comprising a layer of rubber and a layer of material to protect said rubber, a plurality of liquids one of which is mercury contained in said bag, windings of rubber about said bag, and a wear-resist-

ing casing constituting the outer portion of the ball.

45. 6. A playing-ball having a core which comprises a bag having a layer of fabric or other reinforcing material and a layer of rubber, a plurality of incompressible liquids in said bag of different specific gravities, 50 windings about said bag, and a wear-resisting casing constituting the outer portion of the ball.

7. A core for playing-balls comprising in combination a bag or container having therein a plurality of liquids of different specific gravities, said liquids being of such character that they are not soluble in each other.

8. A playing-ball comprising in combination a bag or container having therein a plurality of liquids, such as water and mercury, rubber windings surrounding said bag or container, and a wear-resisting casing surrounding said rubber windings.

60. 9. A playing-ball comprising in combination a bag or container having therein a heavy liquid and a light liquid, the latter of which floats upon the former, rubber windings surrounding said bag or container, 70 and a wear-resisting casing for said container.

75. 10. A playing-ball of the class described comprising in combination a bag or container having therein liquids, such as water and a liquid having a specific gravity different from water, windings surrounding said bag or container, and a wear-resisting casing constituting the outer portion of the ball.

80. This specification signed and witnessed this 25th day of January, A. D. 1916.

WILLIAM R. KNIGHT.
